(57) **CLAIM**

The ornamental design for a shower plate, as shown and described.

DESCRIPTION

FIG. 1 is a top view of a shower plate of the present invention; FIG. 2 is a side view thereof;

FIG. 3 is a cross-sectional side view thereof, taken along the line 3-3 of FIG. 1;

FIG. 4 is a bottom view thereof; and,

FIG. 5 is an enlarged cross-sectional side view thereof, enlarging the sections labeled FIG. 5 in FIG. 3.

The broken line showing in FIG. 5 is included for illustrative purposes only and forms no part of the claimed design.
